UNITED STATES PATENT OFFICE.

SIDNEY C. GILBERT, OF JACKSON, OHIO.

BOTTLE-HANDLING MEANS.

Application filed December 27, 1926. Serial No. 157,354.

The present disclosure of the invention relates to a refrigerator for bottled drinks, in which a plurality of passages are provided to contain rows of bottles filled with 5 drinks of different flavors, each passage being provided with an accessible end for removal of bottles, and with an inlet, it being intended that each time a cold bottle is removed from a passage, another bottle shall 10 be inserted through the inlet.

It is one object of the invention to make novel provision for forcing the passage-contained bottles away from the inlet, toward the outlet, whenever another bottle is to be 15 inserted through said inlet, thus making room for the bottle to be inserted, and insuring that it shall not descend upon a bottle already in the passage.

Another object of the invention is to provide 20 a cover for the inlet, which cover is normally closed, and to make provision whereby this cover may be opened and the passage-contained bottles simultaneously forced away from the inlet toward the outlet.

Yet another aim is to provide a novel construction in which the cover when closed, is 25 in the path along which a bottle to be inserted, may be forced by hand, causing the bottle to strike the cover and move it to open position, at the same time effecting the 30 desired movement of the passage-contained bottle away from the inlet.

Yet another aim is to provide a novel 35 construction and arrangement of parts, whereby the insertion of a bottle into the passage through its inlet, serves to restore the bottle-forcing means to its normal position, in readiness to act when the next bottle is to be inserted, and in the present disclosure, restoring of said forcing means to 40 its normal position, serves also to automatically close the cover for the inlet.

Yet another object is to provide a single, 45 obtuse-angular lever whose upper arm is connected with the cover of the inlet and whose lower arm serves as the means for forcing the bottles toward the outlet when another bottle is to be inserted, said lower arm of the lever also constituting means in 50 the downward path of the ingoing bottle, for restoring the lever to its normal position and at the same time closing the cover.

A still further aim is to provide a construction in which it is impossible to add 55 another bottle to a predetermined number of bottles in the container, until one of such

number has first been removed, making room for the additional bottle to be inserted.

With the foregoing and minor objects in view, the invention resides in the novel 60 subject matter hereinafter described and claimed, the description being supplemented by the accompanying drawings.

Fig. 1 is a top plan view of one of the many forms of refrigerators which may be 65 constructed to embody my invention.

Fig. 2 is a vertical sectional view on line 2—2 of Fig. 1, showing the normal position of parts.

Fig. 3 is a view similar to Fig. 2 but illustrating the manner in which the row of bottles in the passage is advanced, after one bottle has been removed and another is being inserted.

Fig. 4 is a horizontal sectional view on line 4—4 of Fig. 2.

The invention has herein been illustrated and described in connection with a refrigerator and for the purpose of handling bottles. It is to be understood however that 80 containers of other sorts could in some instances be handled with the invention and that the latter is not necessarily used with a refrigerator. Moreover, it is to be understood that while the details herein disclosed 85 may be followed, numerous variations may be made within the scope of the invention as claimed, if found desirable or advisable.

A refrigerator R has been shown embodying an ice chamber C above a base portion 90 B, said base portion projecting forwardly beyond the ice chamber and having a plurality of doors D for giving access to parallel horizontal, front-to-rear passages P to contain the bottles b. At their rear ends, 95 the passages P are provided with vertical inlet throats T, whose mouths M open at the top of the refrigerator behind the horizontal cover C' of the ice chamber C.

Each throat T is provided with a normally closed cover 5 which is slideable rearwardly to open position, as seen in Fig. 3, said covers having their front edges extending upwardly from the plane of the cover C', so that by standing a bottle upon this cover 100 C' and forcing it rearwardly against one of the covers 5, the latter will be forced to the open position of Fig. 3. Novel provision is made whereby this movement of any cover 5 to open position, will automatically advance the row of bottles b in the subjacent 105 passage P, toward the outlet door D of such

passage, it being of course understood that the cover 5 is not opened to permit another bottle to be inserted through the throat T, until the foremost bottle of the row has been 5 removed from the passage P.

In the present disclosure, a substantially vertical, obtuse-angular lever 6 is disposed at the rear side of each throat T and is fulcrumed between its ends as indicated at 7. 10 The upper arm of this lever is connected with the adjacent cover 5, for instance, by positioning it in a groove 8 in the lower side of said cover. When this cover stands closed as in Fig. 2, the upper arm of the lever 6 inclines forwardly across the throat T and the lower arm of said lever then stands vertically behind the row of bottles b in the passage P. We will now assume that the foremost of this row of bottles is 15 removed and sold, and that another bottle is to be inserted into the passage. To accomplish this, the bottle to be introduced, is rearwardly forced against the cover 5, moving the latter to the position of Fig. 3. This movement of the cover rocks the lever 6 about its fulcrum 7, causing its lower arm to forwardly force the row of bottles b, making room for the additional bottle to be 20 inserted. This bottle is now dropped into the mouth M and as it descends through the throat T, it strikes the lower arm of the lever 6, which arm then declines forwardly in the lower portion of said throat. By striking this lower lever arm, the bottle 25 swings the lever again to the normal position of Fig. 2, effecting closing of the cover 5 and at the same time positioning the bottle-forcing means, that is the lower arm of the lever, in readiness to again act, the next 30 time another bottle is to be inserted, after removal of the foremost of the row. In this connection, attention is invited to the fact that when the passage P is full of bottles as in Fig. 2, the lever 6 cannot swing about 35 its fulcrum 7 and consequently the cover 5 cannot be forced open. This insures that no bottle can be dropped into the throat T upon the rearmost of the row of bottles, which would in all probability cause breakage. 40 The cover 5 may be opened and another bottle inserted only after one or more bottles have been removed through the door D.

The present disclosure of the invention is 45 exceptionally simple and inexpensive, yet is efficient, reliable, and in every way desirable. On account of these existing advantages, the general construction herein disclosed is preferably followed. However, within the scope of the invention as claimed, 50 variations may of course be made, as hereinbefore stated.

What is claimed is:—

1. In a bottle handling machine, a passage 55 to contain a plurality of bottles, said passage having an end accessible for removal

of bottles and being provided at a remote point with a bottle inlet, a support along which a bottle may be moved to said inlet, a slidable cover for said inlet disposed in the path along which the bottle is moved on 70 said support, whereby said slidable cover may be forced open by pushing the bottle against it, and means connected with and actuated by said cover for automatically advancing the passage-contained bottles toward 75 said accessible end of the passage each time said cover is opened.

2. In a bottle handling means, a substantially horizontal passage to receive a row of bottles, said passage having a front end 80 accessible for removal of bottles, and at its rear end having a substantially vertical inlet throat, a substantially upright obtuse-angular lever at the rear side of said throat and fulcrumed between its ends, the lower 85 arm of said lever being normally engaged with the rearmost of the row of bottles whereas the upper arm of said lever then inclines forwardly across the throat, whereby rearward forcing of said upper arm incident to inserting another bottle through the throat, will forwardly force the lower arm to advance the row of bottles toward said accessible end of the passage, said lower arm then occupying a forwardly declined 90 position in the downward path of the bottle being inserted through the throat, whereby this bottle will strike said lower arm and restore the lever to its normal position and a normally closed cover for the mouth of said 95 throat rearwardly slidable to open position and connected with the upper arm of said lever.

3. In a bottle handling means, a substantially horizontal passage to receive a row 105 of bottles, said passage having a front end accessible for removal of bottles, and at its rear end having a substantially vertical inlet throat, a substantially upright obtuse-angular lever at the rear side of said throat 110 and fulcrumed between its ends, the lower arm of said lever being normally engaged with the rearmost of the row of bottles whereas the upper arm of said lever then inclines forwardly across the throat, whereby rearward forcing of said upper arm incident to inserting another bottle through the throat, will forwardly force the lower arm to advance the row of bottles toward 115 said accessible end of the passage, said lower arm then occupying a forwardly declined position in the downward path of the bottle being inserted through the throat, whereby this bottle will strike said lower arm and restore the lever to its normal position, a 120 normally closed cover for the mouth of said throat rearwardly slidable to open position and connected with the upper arm of said lever, and a support along which to rearwardly force the bottle to be inserted, said 125 130

cover being in the path of such bottle to be struck and opened by the latter, thereby actuating the lever.

4. In a bottle handling means, a substantially horizontal passage adapted to contain a row of bottles, said passage having a bottle outlet at its front end, a bottle inlet throat at its rear end, and being provided with a portion at said front end for limiting the forward movement of the row of bottles, a normally closed cover for the mouth of said throat, said cover being rearwardly slidable to open position, and a substantially vertical obtuse-angular lever fulcrumed between its ends at the rear side of said throat, the upper arm of said lever being connected with said cover to be shifted

rearwardly by the opening of said cover, the lower arm of said lever normally engaging the rear side of the rearmost bottle of the row and standing substantially in a vertical position, said lower arm being held against forward movement by the row of bottles until the foremost bottle is removed from engagement with said limiting means, whereby said lever locks said cover against opening until said foremost bottle has been removed, opening of said cover being then permitted however for the introduction of another bottle.

In testimony whereof I have hereunto affixed my signature.

SIDNEY C. GILBERT.
